MARKING MACHINE

Samuel R. Swenson, Chicago, Ill.

Application March 14, 1932, Serial No. 598,611

7 Claims. (Cl. 101—39)

This invention relates to improvements in marking machines.

One object of the invention is to provide a machine of sturdy, but simple, construction which requires but little power for operation and into which golf balls or other articles to be marked can readily be inserted, and the necessary adjustments conveniently made for printing thereon a name, legend or the like.

Another object of the invention relates to the provision of means for effecting the ready adjustment of the object to be marked to the proper printing position, the adjusting means serving to hold said object positively in such adjusted position.

A further object of the invention relates to the construction of the die holder or carriage which is self-inking and which, while it is positively actuated by feed mechanism during operation, can be freely withdrawn from the machine for resetting the type or dies.

Other objects of the invention relate to various features of construction and arrangement of parts, which will be apparent from a consideration of the following specification and accompanying drawings wherein

Fig. 1 is a front elevation of a marking device embodying the present improvements and designed particularly for golf balls.

Fig. 2 is an end elevation thereof.

Fig. 3 is a sectional view taken on line 3—3 of Fig. 2.

Fig. 4 is a sectional view taken on line 4—4 of Fig. 3.

Fig. 5 is a broken view of two members, constituting the type or die holder, said members being shown in detached relation.

Fig. 6 illustrates a golf ball with the name printed thereon and one of the supporting rollers shown diagrammatically.

In the drawings, 10 is the base of the supporting structure which preferably is a casting and has an upwardly extending rear web or back 11, the upper end of which comprises a housing 12. In the upper portion of the housing is journaled a shaft 13, having a hand wheel 14 on its outer end. The inner end of the shaft 13 carries a pinion 15, which meshes with the rack formed on the upper horizontal side of the reciprocal die holder or carrier, which is indicated generally by the numeral 16. The holder 16 is shown as being slideable in a horizontal passage 12—a formed in the housing 12. The holder is preferably formed in two parts, 17 and 18, as illustrated in Fig. 5. Member 17 has a rack, 19, along its upper side, and is provided with spacing members 17—a at the ends of its forward face. The space at the forward side between the members 17—a constitutes the die or type holding chamber 20. The complementary member 18 is provided with a

flange 21, which seats on the upper ends 22 of the spacing members 17—a. The flange 21 forms a bearing surface for the upper part of the holder and consequently preferably extends slightly above the upper surface of the rack 19. The vertical flange of the member 18 is provided with a slot 23 for facilitating cleaning and inspection of the die or type holding chamber. As shown in Figure 4, the upper horizontal wall of the opening or slot 23 is formed at a slight elevation above the lower face of the flange 21, whereby the inspection of the contact of the dies with the flange is facilitated. The members 17 and 18 may be riveted or otherwise suitably secured together in the relation described, wherein the recess or the chamber 20 is opened at the bottom for receiving the dies or type which are clamped in position therein by a thumb screw 24, threaded in the one end of the member 17. Spacing blocks or slugs 25 may be inserted between the type or dies 26 and the inner end of the clamping screw 24 to compensate for names or legends of different lengths.

As shown in Figure 3, the ends of the dies or type 26 upon which the printing characters or letters are formed project from the chamber of the holder 16 into a plane substantially tangent to the upper surface of the inking roller 27, which is journaled in a housing 28 which may be integral with the frame of the device. As the holder 16 is moved to the right, as viewed in Figure 3, the characters of the dies contact with the roller 27 and are suitably inked.

The article to be marked, such as a golf ball 29, is placed on two rollers 30, 31. Roller 30 is mounted on a short shaft 32 journaled in the side walls of the recess 33 which is formed in the upper portion of the base 10. Roller 31 is mounted on a shaft 34 secured to two arms of a yokelike member 35 which is slidable in the recess 33 by means of a screw 36, having a knurled operating nut 37 at its outer end. The yoke and the roller 31 can be moved back and forth by means of a screw which is threaded in the end of the yoke. When the roller is moved to the left, as viewed in Figure 3, a ball 29, resting on the two rollers, can be moved with precision to the proper elevation with respect to the printing dies 26. When the handle 14 is rotated, the pinion 15 will move the holder 16 horizontally and the dies will successively engage the surface of the ball which rotates upon the rollers 30 and 31. That is, the rotatable rollers which are shown in the form of spools hold the ball from advancing laterally but permit it to rotate upon a horizontal axis when engaged by the moving dies whereby successive portions of the ball are brought into contact with successive dies or type and the letters of the name thus printed one at a time upon the ball. The rollers 30 and 31 preferably have their frusto-conical

ends so spaced apart by the intermediate cylindrical portions that the pressure of the die upon the ball will cause the latter to contact with and receive additional support by said cylindrical portions. The ball will thus have six points of contact with the supporting rollers and will be held firmly, but rotatably, in printing position. In Figure 6 this relation of the rollers to the ball is illustrated diagrammatically.

10 The holder 16 can be removed freely from either end of the guiding passage 12-a, in which it is shown in Figure 1. This passage is partially closed on the forward side, as shown in Figure 1, by a removable plate 38. During the reciprocating movements of the holder 16, the upper face of flange 21 being slightly above the level of the rack will prevent the teeth of the rack from contacting with the upper wall 12-b of the passage 12-a. The holder is supported by, and slides upon, the lower wall 12-c. A small plate 39 forms a cover for the end of the chamber in which the inking roll 27 is positioned, the plate being supported by the shaft 40 on which the roller is rotatably mounted. The base 10 of the machine has a horizontal chamber in which a drawer 41, for extra dies or type, is provided.

15 In use, the nut 37 is operated to retract the yoke 35 and roller 31 sufficiently to enable the ball 29 to be placed in position from the front of the machine. The nut 37 is then operated to move the roller 31 to the left, as viewed in Figure 3, to elevate the ball to the proper height, as above mentioned. The hand wheel is turned to advance or to reciprocate the holder or carrier 16, to move the dies or type 26 into contact with the ball. 20 The roller 27 inks the type on each movement of the same thereover. To reset the type in the holder 16, the latter is pulled from either end of the housing. The clamping nut 24 is loosened and the type and spacing slugs removed through the bottom opening in the holder, and the new type inserted. Instead of using individual type for each letter, it will be obvious that a linotype slug, having a name cast thereon, may be used. 25 This arrangement is convenient where a machine is owned by a golf club, since each member may have a cast slug bearing his name and thus can readily mark his new balls. The same practice can be followed by sporting goods stores, that is, they may have slugs made for their regular customers and mark therewith all the balls purchased by such customers.

30 While I have shown and described a golf ball marking machine embodying my improvements, it will be obvious that other objects may be marked as well, and that various detailed changes may be made in the structure without departing from the scope of my improvements. The terms "top", "bottom", "horizontal" and similar terms used in the specification, are employed in a descriptive sense for the purpose of simplifying the description, and not in a limiting sense, as the relative arrangement of many of the parts may be changed, as circumstances may require. Therefore, I do not wish to be restricted to specific details of construction and relative arrangement of parts, except as required by the prior art.

35 I claim:

1. A device of the class described comprising a rotary support for an article, a slidable rack member for holding dies in a plane tangent to said article, and a pinion meshing with said rack member for moving said dies in succession into contact with said article as the latter is rotated on said support by contact with said dies.

2. A device of the class described comprising a frame, a rotary support in the lower portion thereof, said frame having a passage above said support, a slidable rack member in said passage for holding dies in a plane tangent to an article on said support, and a pinion meshing with said rack member for actuating the same in said passage for moving said dies in succession into contact with said article as the latter is rotated on said support by contact with said dies. 85

3. A device of the class described comprising a frame having a shaft mounted in a fixed portion thereof, a roller on said shaft, a second roller coacting with said first roller to form a support for an article, printing means spaced from said support, and means for adjusting said second roller for moving said article into position with reference to said printing means, said adjusting means comprising a slide member having a threaded screw for moving said roller toward or from said first roller. 90

4. A printing device for golf balls comprising a frame having a guide passage therethrough, a die holder reciprocal within said passage, the upper surface of said holder comprising a rack, a manually operable pinion journaled in said frame and adapted to engage said rack for reciprocating said holder, said holder having a slot in the lower surface through which said dies project, and means for rotatably supporting a ball in printing position with respect to said dies as said holder is reciprocated. 100

5. A golf ball marking device comprising a base having a recess in the upper surface thereof, a pair of ball supporting rollers in said recess, a slide in said recess on which one of said rollers is mounted, means on the exterior of said base for adjusting said slide and roller relatively to said other roller for vertically adjusting a ball resting on said rollers, a housing above said base having a horizontal passage extending throughout, a die carriage slidable within said passage and adapted to carry die member with the character ends of the same projecting downwardly into contact with a ball on said rollers, said carriage having a rack on a surface thereof, and a manually operable pinion journaled in said housing for engaging said rack for reciprocating said carriage. 110

6. A golf ball marking machine comprising a supporting structure, an adjustable anti-friction support for a ball within said structure, said structure having a horizontal passage in the upper portion thereof for receiving a reciprocal die carriage, said carriage comprising a pair of coacting plates spaced apart intermediate the ends thereof to define a die receiving chamber, means for clamping a die within said chamber, one of said plates having a rack on its upper side, the lower side thereof and the upper side of said other plate constituting bearing faces for said carriage, and a manually operable pinion in said supporting structure engaging said rack for actuating said carriage within said passage. 125

7. A printing device for golf balls comprising a standard having a base, a side flange, and a top portion secured to said flange and overhanging said base, means on said base for rotatably supporting a ball, a reciprocable die holder carried by said top portion, means for actuating said holder for moving the dies in succession into contact with the top of a ball on said support and a device below the path of travel of said die holder for inking said dies during the reciprocation of said holder. 140
